UNITED STATES PATENT OFFICE

126,626

DESIGN FOR A LUGGAGE CASE OR SIMILAR ARTICLE

Samuel Katz, Chicago, Ill.

Application February 21, 1941, Serial No. 99,161

Term of patent 7 years

To all whom it may concern:

Be it known that I, Samuel Katz, a citizen of the United States and resident of Chicago, in the county of Cook and State of Illinois, have invented a new, original, and ornamental Design for a Luggage Case or Similar Article, of which the following is a specification, reference being had to the accompanying drawing, forming a part thereof.

Fig. 1 is a perspective view of a luggage case or similar article showing my new design.

Fig. 2 is a side elevational view of the same.

The other side and end of the article illustrated in the drawing are substantially like the side and end shown.

I claim:

The ornamental design for a luggage case or similar article, substantially as shown and described.

SAMUEL KATZ,
